(57) **CLAIM**

The ornamental design for an exhaust collector, as shown and described.

DESCRIPTION

FIG. 1 is a first perspective view of the exhaust collector of the present invention;

FIG. 2 is a second perspective view thereof;

FIG. 3 is a front elevational view thereof;

FIG. 4 is a top plan view thereof;

FIG. 5 is a bottom plan view thereof; and,

FIG. 6 is a right side elevational view thereof, the left side elevational view being a mirror image thereof.

The broken line showing of environment is for illustrative purposes only and forms no part of the claimed design.
